UNITED STATES PATENT OFFICE.

HENRY H. COOLEY, OF BATTLE CREEK, MICHIGAN.

IMPROVEMENT IN PISTONS FOR FORCE-PUMPS.

Specification forming part of Letters Patent No. 36,702, dated October 21, 1862.

To all whom it may concern:

Be it known that I, HENRY H. COOLEY, of Battle Creek, in the county of Calhoun and State of Michigan, have invented a new and useful Improvement in Pistons for Force-Pumps; and I do hereby declare that the following is a full, clear, and exact description of the same, reference being had to the accompanying drawing, making a part of this specification, said drawing being a vertical central section of my invention.

This invention consists in constructing the piston with two water-passages and a valve-chamber, the latter being provided with a ball-valve and communicating with a tubular piston-rod, all being arranged in such a manner and in connection with the pump-cylinder, which is provided with suitable valves, so as to throw a continuous stream.

The object of the invention is to simplify and economize in the construction of force-pumps, and at the same time augment their efficiency by a perfect working of parts, which will not be liable to become deranged by use.

To enable those skilled in the art to fully understand and construct my invention, I will proceed to describe it.

A represents a cylinder, which is divided by partitions *a* into three compartments, *b*, *b'*, and *c*. The compartment *c* is at the center of the cylinder, and is closed at its bottom, but communicates at its upper end with the tubular piston-rod *B*, which is screwed into the upper end of said compartment, as plainly shown in the drawing. The compartment *c* is the valve-chamber, provided at two opposite points with openings *d* *d'*, which are closed alternately by the valve *C*, the latter being spherical and sufficiently smaller in diameter than the chamber *c* to admit of a free passage of water through *c* from one opening, *d* or *d'*, when the other is closed. The opening *d* forms a communication between the chamber *c* and the compartment *b*, while the other opening, *d'*, forms a communication between *c* and the compartment *b'*, the latter, *b'*, communicating with the pump-cylinder at the bottom of cylinder *A*, and the former, *b*, communicating with the pump-

cylinder at the upper end of cylinder *A*. The cylinder *A* is the piston, and it is fitted within the pump-cylinder, (shown in red, and designated by *D*,) said cylinder being provided with a vertical side water-passage, *E*, having a valve, *F*, opening upward in its bottom, and communicating at its upper end with the upper end of the pump-cylinder *D*, as shown at *e*. The bottom of the pump-cylinder *D* is also provided with a valve, *f*, opening upward. The piston *A* is fitted watertight in the pump-cylinder *D*, and is allowed to work freely up and down therein. When the piston rises, a suction is of course formed in the lower part of the pump-cylinder *D*, the valve *f* opening and the water passing through it, while the water in the pump-cylinder above the piston *A* passes down through the compartment *b*, through opening *d*, into chamber *c*, and thence up through the tubular piston-rod *B*. (See black arrows.) When the piston descends, the valve *f* closes, and a suction is produced in the upper part of the pump-cylinder above the piston and in the water-passage *E*, the valve *F* opening upward, and the water passing up through *E* into the upper part of *D*. The spherical or ball valve *C* is operated by the action of the water, the former closing the opening *d'* and cutting off the communication between *c* and *b'* as the piston ascends, and as the latter descends closing the opening *d* and cutting off the communication between *c* and *b*, space, as previously alluded to, being allowed between the ball-valve *C* and the opening which is not closed by the latter, to admit of the free passage of the water up through *c* into the tubular piston-rod *B*. Thus by this simple arrangement a very efficient force-pump is obtained, and one which is not liable to become deranged by use or to get out of repair.

I would remark that the lower horizontal partition, *a*, on which the valve *C* rests, is made detachable in any proper way to admit of the insertion of the valve *C* in the chamber *c*, and its removal therefrom when necessary.

I do not claim as new the pump-cylinder *D*, provided with a side water-passage, *E*, for that is old and in common use; but

I do claim as new and desire to secure by Letters Patent—

The piston A, divided into three compartments, b b' c , the latter, c , communicating with b b' by means of the openings d d' , and provided with the ball-valve C, in combination with the tubular piston-rod B, all ar-

ranged to operate in connection with a pump-cylinder provided with a side water passage and suitable valves, as set forth.

HENRY H. COOLEY.
